UNITED STATES PATENT OFFICE.

JOHN G. SHERWOOD, OF BUCYRUS, ASSIGNOR TO HIMSELF AND JAMES ARMSTRONG, OF TOLEDO, OHIO.

IMPROVEMENT IN HOISTING APPARATUS.

Specification forming part of Letters Patent No. 146,557, dated January 20, 1874; application filed November 19, 1873.

To all whom it may concern:

Be it known that I, JOHN G. SHERWOOD, of Bucyrus, in the county of Crawford and State of Ohio, have invented an Improved Hoisting Apparatus, of which the following is a specification:

My apparatus is more especially adapted for hoisting articles having polished surfaces, such as columns, obelisks, &c. Its object is securely to clasp and hold the article without injury thereto; and my improvement consists in a novel apparatus for clamping the article to be hoisted between surfaces of vulcanized rubber, or other equivalent elastic material possessing the quality of great resistance from its frictional contact to any lateral movement of the article grasped, and of being also impervious to air or moisture, whereby not only is any lubrication of the clamping-surface by infiltration prevented, but the atmospheric pressure causes the clamping-surface to act as a "sucker," such as the school-boy's well-known plaything, and thus adds greatly both to the lifting power and safety of the apparatus.

In the accompanying drawings; Figure 1 represents a view in perspective of an apparatus embodying my invention in the best way now known to me, the said apparatus, in this instance, being adapted to grasp an obelisk. Fig. 2 represents a side elevation thereof, partly in section. Fig. 3 represents a horizontal section on the line $x x$ of Fig. 1.

Stout beams, blocks, or slabs A, preferably of wood, are strengthened at intervals by horizontal cross-bars B C D, of metal, by preference let into the wood flush with its surface,

and having their ends bent inward and secured to the blocks. Vertical straps E are likewise strongly secured to these blocks, and to the cross-bars, which they cross at their points of intersection. These straps are provided with rings e, to which hoisting-ropes may be secured. Hooks F are likewise secured to these straps, and to the blocks. The inner face of each block is lined with a continuous covering or pad, P, of thick gutta-percha or vulcanized rubber, such, for instance, as that used for heavy belting. This cover or pad is riveted or fastened at its ends to the edges of the block in such manner as to leave an unbroken grasping surface. The article to be hoisted is clamped between these surfaces or pads by means of screw-bolts G, which pass through holes in the blocks on each side of the article to be hoisted. These screw-bolts are provided with clamp-nuts g, to clamp the blocks tightly upon the article to be hoisted. This clamping expels the air from between the rubber surface and that of the stone, and thus greatly increases the power with which the article to be hoisted is grasped. Experience has amply demonstrated the effectiveness of my improved apparatus.

I claim—

In a hoisting apparatus, the combination of the elastic-pads, the blocks, and the clamping-screws, substantially as set forth.

In testimony whereof I have hereunto subscribed my name.

JOHN G. SHERWOOD.
